(57) **CLAIM**

The ornamental design for a florescent task lamp, as shown and described.

DESCRIPTION

FIG. 1 is a first perspective view of a florescent task lamp; FIG. 2 is a front view of the florescent task lamp, with the cord broken away to indicate indeterminate length; FIG. 3 is a first side view of the florescent task lamp; FIG. 4 is a second side view of the florescent task lamp; FIG. 5 is a back side view of the florescent task lamp; FIG. 6 is a top side view of the florescent task lamp; and, FIG. 7 is a bottom side view of the florescent task lamp. The broken line showing is for illustrative purposes only and forms no part of the claimed design.
